DANCING TOY

Raymond H. Turner, St. Louis, Mo.

Application July 2, 1949, Serial No. 102,840

1 Claim. (Cl. 46—137)

1

This invention relates to dancing toys and particularly to dancing toys having a flexible stage and a dancing figure suspended above the stage by the operator. Dancing toys heretofore constructed have used paddle-like members to be clamped to a table or sat upon, or box-like stages over which figures were fixedly suspended and which were made to oscillate by impressing motion directly on the platform. Dancing figures heretofore made have generally been equipped with flat shoe members, so constructed that the contact between platform and shoe was practically entirely at the toe end of the shoe.

One of the objects of this invention is to provide a dancing toy with an improved stage providing a rest for the arm of the operator and a more sensitive action.

Another object is to provide an articulated dancing figure having a more life-like action.

Further objects will appear from the following description taken in connection with the accompanying drawings in which:

Figure 1 is a side view of one form of stage showing the position of the operator's arm and the mode of suspending the dancing figure.

Figure 2 is a plan view of the stage shown in Figure 1;

Figure 3 is a side view illustrating another embodiment of this invention;

Figure 4 is a side view illustrating still another embodiment of this invention;

Figure 5 is a side view illustrating still another embodiment of this invention, showing a compound platform;

Figure 6 is a side view illustrating still another embodiment of this invention;

Figure 7 is a section through 7—7 of Figure 5 showing the construction of one embodiment of compound platform;

Figure 8 is a section through 8—8 of Figure 6, 40 showing another embodiment of compound platform;

Figure 9 is a front view showing the articulated leg members of the dancing figure;

Figure 10 is a side view of a lower leg member of Figure 9 showing the terminal shoe member.

According to an illustrative embodiment of this invention, a stage is provided having a base to which a flexible member long enough to support the forearm of the operator and to allow the operator's fingers to rest thereon, is attached. The unattached end of the flexible member is provided with a platform. The platform may be derived from the flexible member alone or it may be a compound platform with an intermediate resilient

composition such as cork or rubber, either solid or in such form, as strips or "islands," as to leave a portion of the intermediate space open, and an upper resonant platform member of wood, plastic, metal or the like. The dancing figure to be suspended above the platform by the operator is provided with articulated legs terminating in shoe-like members which are designed to make contact with the platform with both the heel and toe portions when the flexible member is caused to oscillate by the operator, the toe portion striking the platform slightly more frequently than the heel portion when the figure is suspended in a vertical position.

15 Referring to the accompanying drawings, and more particularly to Figure 1, 1 designates a flexible member. The free end of flexible member 1 provides a simple platform 2. The opposite end of flexible member 1 is attached to supporting members 3. In the embodiments shown in Figures 3, 5 and 6, supporting members 3 are attached to lower base member 4. As shown in Figures 5—8, compound platform 5 is composed of simple platform 2, resilient intermediate member or members 6, and upper member 7.

20 The resilient intermediate members 6 may be of any suitable material. Rubber may be used to produce a lively action. A solid sponge member reduces the sound. Cork has been found exceptionally useful in the hollow compound platform, giving a springy action and supporting the upper platform member 7 securely. The arrangement of the intermediate members is subject to many modifications. Strips may be used to enclose 2, 3 or 4 sides of the simple platform. Interior strips may be used, or supporting "islands," disks or springs may be employed.

25 In all of the embodiments shown, the length of the flexible member 1 is sufficient so that the forearm of the operator may rest thereon and be supported by the supporting members 3, and the fingers of the operator may at the same time rest upon the flexible member 1, short of the platform. In the preferred embodiment illustrated in Figure 6, further support for the forearm of the operator is provided by an extension of the flexible member 1 rearwardly of supporting members 3 and joining with base member 4. In this embodiment, the flexible member 1 and base member 4 may be formed in one piece or be made separately. The forwardly extending section of base member 4 in this embodiment extends beyond the stage's center of gravity and hence renders the stage very stable. The step-like members on the base member in Figure 6 serve to enhance the appearance

of the device and at the same time contribute weight to the base member. The supporting members 3 may, of course, be enclosed at each side.

Dancing figure 8 is suspended above the platform by rod 9, as shown in Figure 1. Referring now to Figures 9 and 10, leg members 10 and 11 of dancing figure 8 are tapered at their upper ends 16 and provided with counter-sunk holes 12, which may be bushed with metal. Lower leg member 11 terminates in shoe member 13, having a heel portion 14 and toe portion 15.

Heel portion 14 and toe portion 15 of shoe 13 are shaped and proportioned to permit both portions to engage the oscillating platform, as shown in Figure 1, with a slight preponderance of engagement with the toe portion. In order best to accomplish this it has been found that the heel portion, shaped as shown in Figure 10, should constitute on the order of 40% of the total length of the shoe member along its base.

In operation, the dancing figure 8 is suspended by the operator above platform 2 by means of rod 9, as illustrated in Figure 1. The other arm of the operator rests upon the section of the flexible member 1 supported by the members 3 while the operator's fingers rest lightly and naturally on the flexible member toward its free or platform end, though not on the platform itself. When the flexible member is tapped lightly with the fingers platform 2 immediately begins to oscillate, making contact with the figure's shoe members 13 both at toe 15 and heel 14, causing the figure to dance in a life-like manner. The counter-sunk joints 12 and tapered ends 16 of the leg members allow sufficient side play to increase this life-like appearance and to allow a greater variety of motion than is otherwise possible. Variations in the dancing may be obtained by increasing and decreasing the tempo and force of the operator's tapping, by varying the distance above the platform at which the figure is held, and by inclining the figure somewhat from the vertical, from back to front and side to side. When a compound platform is used, the action of the figure is even more life-like and vigorous.

A support may be placed under the platform when the device is not in use to relieve any strain which otherwise will be present in flexible member 1.

The embodiment of the member illustrated in Figures 1 and 2 is, of course, the most simple, lightest and cheapest construction in which separate supporting members are used. On the other hand there is a tendency for such a stage to creep when in use, and there is some difficulty in making the stage self supporting, so that the forearm of the operator must be relied upon to steady the stage when in use. The tendency to creep is somewhat reduced by the construction shown in Figure 3. The same difficulty obtains in the construction shown in Figures 4 and 5, but to a less extent, since the tendency of the flexible member to spring in the space between the supporting mem-

bers is reduced. In the construction shown in Figure 6, the difficulties encountered with the other constructions are completely eliminated. The forwardly extending base member renders the stage completely self supporting. In the light of the present disclosure it is clear that the base members of the embodiment shown in Figures 3 and 5 may also be extended forwardly to stabilize the stage.

A dancing toy is thus provided with a simple, sturdy stable stage which provides a convenient support for the arm of the operator, but which is sensitive to light tapping and to slight variations in tapping force and tempo; and with a dancing figure, the construction of the leg and feet members of which is such that a great variety of life-like motions are imparted.

It is obvious that the invention is capable of various modifications without departing from the spirit of the invention, as for example, the contouring of the dancing figure to conform to the body contours of a human being or variations in supporting members 3, base members 4, or intermediate resilient members 6.

Having thus described the invention, what is claimed and desired to be secured by Letters Patent is:

A stage for a dancing figure having feet, said stage being manipulatable by a human operator, comprising, a base consisting of spaced supporting members, and a flexible member mounted on and projecting from said base and provided with a platform at its free end, the said base being of a length sufficient to support the elbow and a part of the forearm of the operator and the projection of said flexible member beyond the base being sufficient to permit the operator to tap the flexible member with one hand while suspending the figure above and with its feet touching the platform, said platform comprising a lower plane member formed from the said flexible member, intermediate discontinuous resilient supporting members and an upper plane member of resonant material.

RAYMOND H. TURNER.
